P. F. SPERY

INK PAD

Filed Oct. 1, 1920

Inventor
Philmore F. Sperry

By Fisher, Towle, Clapp, Doane Atty's.

UNITED STATES PATENT OFFICE.

PHILMORE F. SPERY, OF CHICAGO, ILLINOIS, ASSIGNOR TO SENGEBUSCH SELF-CLOSING INKSTAND COMPANY, OF MILWAUKEE, WISCONSIN, A CORPORATION OF WISCONSIN.

INK PAD.

Application filed October 1, 1920. Serial No. 414,045.

To all whom it may concern:

Be it known that I, PHILMORE F. SPERY, a citizen of the United States, residing at Chicago, county of Cook, and State of Illinois, have invented certain new and useful improvements in Ink Pads, of which the following is a specification.

The object of this invention is the production of an efficient, serviceable, convenient, and ornamental, inking pad for rubber and other hand stamps, in which the pad proper comprises a series of preferably connected, reversible, and removable, elements, comprising a base or board which is not ink-absorbent, over which an inked ribbon is stretched, which pad, when exhausted of ink, may be re-inked, or discarded and replaced by a new pad. To accomplish this result, I construct this stamp-inking device in the preferred embodiment of my invention, as shown in the drawings, in which—

Fig. 1 is a perspective view of the device;
Fig. 2 is an end elevation of the same;

Fig. 3 is a transverse sectional elevation on line 3—3 of Fig. 8;

Fig. 4 is a plan of the inking pad proper, detached from the holder or container;

Fig. 5 is an edge view of the same;

Fig. 6 is an edge view of a single, detached, inking pad;

Fig. 7 is a similar view showing a slightly modified construction, the inked ribbon being wound a number of times around the board; and

Fig. 8 is a longitudinal sectional elevation on line 8—8 of Fig. 2, the inked ribbon in all the views being exaggerated in thickness to more clearly illustrate the device.

Like parts are designated by the same character or symbol of reference in all the figures.

A, in the drawings designates the base of this device, which is, preferably, rectangular in form and has a top part B, preferably smaller in length and width than the base A, and of suitable height. The upper surface of this part B is of such material as to be non-absorbent of ink, the base A and the part B being preferably of wood, although steel stamping or casting may be resorted to without departing from the scope of my invention. When made of wood, the upper

surface of the part B is preferably varnished, for the object stated.

Supported upon the base A, and over the upwardly-projecting part B, there is removably placed a container C, comprising a rectangular frame having a width corresponding to the width of the member B, and of a length somewhat longer than the corresponding dimension of the part B. This container is of an inverted, box-shaped contour, the bottom 12 of which has a rectangular cut-out portion 13, or sight, the remaining part of the bottom affording flanges against which the ink pad proper bears.

To the container C there is hingedly connected a cover D, there being on said cover, at opposing margins, lugs or ears 15, which lugs are punctured to receive pins 16 engaging the end walls of the container C. The length of these lugs is such that when the cover D is in opened condition and standing at right angles to the base, as shown in Figs. 1, 2, and 3, the preponderance of weight of the cover causes it to retain the vertical position, the rear margin 17 of the cover in this case bearing against the rear wall of the container C.

In the front and rear walls 18, 19, of this container, there are L-shaped slots 20, affording, in conjunction with pins 21, a locking means known by the term "bayonet catch", whereby the container can be removed from the base A by sliding it in the direction indicated by the arrow x, in Fig. 8, the part B being shorter than the length of the container to permit of this longitudinal movement of the container.

The container C is sufficiently deeper than the member B, to afford therein above the part B, and below the inwardly-extending flanges 12, a space in which the inking pad proper, E, is located. This inking pad proper comprises one or more plates 23, preferably made of cardboard of proper thickness, which board is, preferably, rendered non-absorbent of ink by suitable treatment; and it is of a length and width to fit into the container, by an easy fit. Over this board 23, there is trained or stretched an inked ribbon 24, said ribbon being, preferably, wound lengthwise around the board 23, and of one or more layers.

I employ a multiplicity of these pads

which, when superposed, are sufficiently elastic and resilient to form a perfect cushion for a hand stamp when pressed onto the upper surface of the pad; but in the preferred embodiment of my invention, I place a number of these boards 23, end-for-end and slightly spaced apart, as illustrated in Figs. 4 and 5, and stretch the inked ribbon over all of these boards, and then stitch the inked ribbon along the end margins of the board, by stitches 25. This construction permits the pads being folded one upon the other in such manner that any of the inked faces of the ribbon may be placed uppermost, and when exhausted of ink, be turned over to present a new face uppermost. These faces may be re-inked in the usual manner; but in view of the fact that the ink pads form a separate article of commerce and are sold at a very reasonable figure, the public in general prefers to discard an exhausted pad and to replace it with a new one.

The container with its cover is preferably made in sheet metal, which is at once cheap, and which lends itself admirably to ornamentation in any of the well-known processes of electroplating, japanning, etc., and thereby produces a very ornamental article.

It is a well-known fact that rubber, and other hand, stamps when being inked by being pressed upon an inked ribbon properly cushioned instead of an inking pad, the main portion of which is felt saturated with ink, afford a much cleaner and clearer impression, and that the objectional feature of re-inking is avoided in my device, when the exhausted pads are discarded.

While I have hereinbefore described the preferred embodiment of my invention, I desire it to be distinctly understood that I am aware that details of construction may be changed, and parts omitted, without departing from the scope of my invention.

I claim as my invention:

- 45 1. An inking pad comprising a plurality of sections connected together along their edges to fold together in optional superposed relations for selectively exposing the opposite faces of the various sections.
- 50 2. In an inking pad, the combination of a plurality of sections hinged together so as

to fold in superposed relation, each of said sections comprising a plate having an inked sheet of fabric on opposite sides thereof, so that each section serves as a reversible inking pad for rubber stamps and the like. 55

3. In an inking pad, the combination of a double length of inked ribbon, and a plurality of plates interposed end to end between the lengths of the ribbon and having the latter connected with the plates at their ends to afford a hinged connection between the plates and provide a fabric-covering on the opposite faces of each plate for inking rubber stamps and the like. 60

4. In a device of the class described, the combination of an ink pad comprising a plurality of inking sections hinged together along their edges to fold in optional superposed positions for selectively exposing the opposite sides of the various sections, and a casing for locking the sections in superposed relation and adapted to expose the outer face of the uppermost section. 70

5. In a device of the class described, the combination of a sectional inking pad composed of a plurality of relatively stiff plates, an inked fabric strip embracing the opposite sides of the plates and forming a collapsible connection therebetween, whereby the sections are adapted to fold together in superposed relation, and a holder for the pad comprising two parts for clamping the sections of the pad therebetween in superposed relation, one of said parts being provided with an opening for exposing the outer face of the uppermost section of the pad. 75 80 85

6. An inking pad for hand and other printing stamps, comprising a base, an upwardly-extending element on said base, a frame on said base and surrounding said element, said frame having an opening or sight, a cover hingedly connected to said frame, there being in opposing walls of said frame L-shaped notches and in the upwardly-extending element pins engaging said notches, the longitudinal dimensions of said element being shorter than the longitudinal dimension of said frame, and an inking pad proper in said frame. 90 95
